Henry Clark New London Ct

Letters Patent

The schedule referred to in these Letters Patent and making part of the same containing a description in the words of the said Henry Clark himself of this improvement in the rib for saw cotton Gins.

To all to whom these presents shall come: Be it known that I Henry Clark of New London in the County of New London and State of Connecticut have invented a new and useful improvement in the Rib for saw cotton Gins and the following is a full and exact description of said improvement. First. The Rib is made in two parts viz. by an iron foundation and a face of steel or hard wood. The latter is fastened firmly to the former with scrogs, screws or catches. Fig. 1. is the foundation. Fig. 2. the face. Fig. 3. the Rib finished. The length, width, thickness and shape of the Rib will vary according to the size of the Gin and the fancy of the maker as may the face vary in all these respects without affecting my improvement. The superiority of my improved Rib over all others in use is obvious in the following particular - first. The Rib is more perfect. Dr When the face of the Rib becomes so worn as to need repairing it is easily taken off the foundation and another one put in its place for one fourth the ordinary expense of repairing. 2^d The improved Rib can be afforded at a less price than any other. The manner of making the improved Rib is as follows. Take iron rolled or hammered one half inch wide, by three sixteenths thick and sixteen inches long, punch five holes. Three of them in the usual place for fastening the Rib to the frame, the other two for fastening the face on. And this is the shape desired this is the foundation. Then take the steel or iron rolled one eighth of an inch thick. cut it with a saw or shear the shape required punch two holes to correspond with the holes in the foundation. fasten them together by screws, nuts or catches in such a man-

now that the face can be easily taken off the foundation, and a new one put in its stead, harden and polish the face and the Rib is done. What I claim as my own invention and not previously known in the above described Rib is the making it in two parts viz a new foundation and a shell or hardened iron face fastened to together either with screws nuts or catches so that when the face becomes worn by use or other cause is injured it can easily be detached from the foundation and a new face put in its place, and this is all I claim heretofore the Rib has been made with an iron foundation and a face of shell added together. The superiority of my invention is this, that whenever the face of the Rib by use either causes becomes worn or injured so as to require repairs or a new face the old face can readily be detached from the foundation and another face put in its stead whereas according to the former method of securing the face to the foundation by holding great difficulty and expense was necessarily incurred in order to remove an old face and replace that or a new one.
